UNITED STATES PATENT OFFICE.

JOHN DEMAREST, OF NEW YORK, N. Y.

CISTERNS FOR WATER-CLOSETS.

SPECIFICATION forming part of Letters Patent No. 269,921, dated January 2, 1883.

Application filed August 21, 1882. (No model.)

To all whom it may concern:

Be it known that I, JOHN DEMAREST, of the city and State of New York, have invented an Improvement in Cisterns for Water-Closets, 5 of which the following is a specification.

In Letters Patent No. 260,952, granted to me, a cistern is shown with a pipe leading to the water-closet and a valve seat at the upper end of said pipe and within the cistern, and a 10 valve at the lower end of a tube that is guided by a ring and held up when lifted by the action of a float and lever, the valve dropping when sufficient water has run from the cistern to allow the float to descend and liberate the 15 tube and valve.

My present invention is for producing a preliminary and after wash to the closet by combining with the cistern two of said valves and arranging them in such a manner that one 20 valve is open as the water-closet seat or platform is depressed, and thereby producing a preliminary wash, and it closes automatically as the water descends to a predetermined level. The other valve is opened when the water-closet seat or platform rises and the water 25 flows until the valve closes automatically, washing or flushing the closet.

In the drawings, Figure 1 is a plan view of the cistern and valves. Fig. 2 is a vertical section at the line xx , and Fig. 3 is a detached view of part of the valve-tube and float.

The cistern a , pipe d , leading to the water-closet, valve-seats e , valves i , tubes f , ring-guides m , standards e' , levers u' , and floats r are substantially the same as shown in the aforesaid patent, to which a reference is hereby expressly made. I have, however, improved upon the same by providing a neck, 3, around the tube f , and forming the end of the 35 lever u' as a pawl to engage the upper offset of the neck and support the tubular valve by a positive device, instead of depending on friction. When the valve is allowed to close upon its seat there is a column of water in the 40 pipe below the valve, and this runs down rapidly into the closet, and air is drawn in at the upper end of the tubular valve-stem. In practice I found that when the tubular valve-stem was made parallel, or nearly so, as in my aforesaid patent, the rush of air into this pipe produced a very disagreeable whistling noise. By 45

flaring the upper end of this tubular valve-stem, as shown at f^2 , the aforesaid difficulty is removed, or nearly so, as the air passes into the pipe with but little noise. I also provide 50 a passage-way in the cistern or a branch pipe below the same at H , uniting the pipe that leads to the water-closet with the two valve-seats. Both valves, levers, and floats are the same, except that in the valve appliances at 55 the right in Fig. 2, and designated R , the float-lever is bent so as to stand at a higher elevation than the float of the left-hand appliances marked L , and these are to be so constructed, proportioned, and arranged that the 60 right-hand valve, when raised, will be allowed to drop automatically when the water has descended to a given level, (here designated as 10.) The float at L will still be operative, and its lever will hold up the left-hand valve, 65 if raised, until the water has still further descended in the cistern—say to the level marked 11. Hence, if the valve at R is raised just before the closet is used, water will run out of the cistern as a preliminary wash, and then 70 automatically stopped by the valve being dropped when the water has descended to 10, and if the valve of L is raised after the closet has been used water will be allowed to run out until the lowest level, 11, is reached, and the 75 valve of L will then be dropped automatically and the flow of water to the closet stopped.

I remark that, although I prefer the tubular valve-stems shown, the operation will be the same if the valve-stems are solid; and I am 80 not limited to any particular kind of valve or stem or appliance for holding the valves up by the action of the floats or dropping the same automatically by the descent of such floats.

In order to operate the valves at R and L 85 by the movement of the water-closet seat, or by a platform or step on the floor, or by the opening and closing of the door of the water-closet, any suitable mechanical appliance may be resorted to, as valves for closet-cisterns have 90 heretofore received motion from such sources. I, however, prefer and use the devices next described.

n is a lever upon a fulcrum, o , with a weight, 95 17. At the other end of the lever there is a 100 link, s , to the wire or chain leading to the seat or other source of motion.

Upon the lever *n* are double-acting latches 20, pivoted at their upper ends to the lever and having catches 21 at their lower ends adapted to grasp the collar 22 at the upper end of the valve-stem. Hence, when the link *s* is pulled upon by depressing the seat or platform, the lever *n* is moved, the weight 17 lifted, and the valve at *R* lifted to allow the aforesaid preliminary wash to run. It is, however, necessary to automatically disconnect the catches 21 as the lever and latches 20 approach the end of the upward movement. This is effected by the cam-projections 23 on 20 coming in contact with the cross-bar *S'*, and moving 21 away from 22, and leaving the valve *R* under the control of its lever and float. As the lever *n* is moved and the weight raised, as aforesaid, the latches 30 (at the opposite side of the lever-fulerum to the latches 20) descend and their catches 31 come below the collar 32 of the left-hand valve-stem *L*. Hence when the closet-seat is liberated by the person rising from the same the lever-weight falls, and by the latches 30 and catches 31 the collar 32 and its valve are lifted, allowing the after flow of water to take place to wash out the closet, the catches 31 are disengaged automatically from 32 by the cams 33 on 30 coming in contact with the cross-bar *S'*.

It is to be understood that the cross-bar *S'* may be mortised for the catches to pass through, or the cross-bar may be notched or have pins or projections that act against the cams 23 and 33 to move the latches as the lever reaches its extreme movement in one direction or the other.

I claim as my invention—

1. The combination, with a water-closet cistern, of two valves, mechanism for raising such valves, floats, and levers for holding up such valves and for allowing the same to drop automatically when the water in the cistern descends to the two different levels, substantially as set forth. 40

2. The combination, with the cistern-valve, 45 of a stem having a neck, a guide for such stem, a float and a lever having a pawl to engage such stem and support the valve, substantially as set forth.

3. The combination, in a water-closet cistern, 50 of two valves, two floats, and means for holding up the valves and for allowing the valves to drop automatically at different levels of the water, a lever and weight and catches on the lever at opposite sides of its fulcrum for alternately raising the valves and means for disconnecting the catches, substantially as set forth. 55

4. The combination, with the water-closet cistern, of a valve, a stem, a guide for the stem, 60 latches for lifting the valve and stem, a float, lever, and pawl for holding up the valve and for allowing it to drop automatically, substantially as specified.

5. The combination of the water-closet cistern and the valve, the tubular stem to the valve having an open flaring upper end, for the purposes set forth. 65

Signed by me this 15th day of August, A. D. 1882.

JOHN DEMAREST.
